(57) **CLAIM**

The ornamental design for a visor, as shown and described.

DESCRIPTION

FIG. 1 is a front perspective view of a visor showing my new design;

FIG. 2 is a front view of the visor shown in FIG. 1;

FIG. 3 is a rear view of the visor shown in FIG. 1;

FIG. 4 is a top view of the visor shown in FIG. 1;

FIG. 5 is a bottom view of the visor shown in FIG. 1;

FIG. 6 is a left side view of the visor shown in FIG. 1; and, FIG. 7 is a right side view of the visor shown in FIG. 1.

The broken lines showing of the nose piece and portions of the side arms of the visor are for illustrative purposes only and form no part of the claimed design.
